PRECISION CONTROLLED FINISHING AND
SIZING DEVICE

Charles Marion Watts, Elkhart, Ind.

Application December 6, 1945, Serial No. 633,163

5 Claims. (Cl. 51—134.2)

1

This present invention relates to apparatus arranged for abrading and truing cylindrical surfaces.

The primary object of this invention is a device to replace the conventional stone holder on any general purpose finishing machine.

Another object of the invention is the design of a device for finishing cylindrical surfaces, both internal and external, to a predetermined dimension while the device is controlled by an adjustable stop preventing overrunning of the desired dimension.

Another object of the invention is the provision of a device that will accurately produce the predetermined dimension to .000020 inch tolerance.

Another object of the invention is the provision of a device of the class described when equipped with an electronic gage which will indicate at all times the diameter of the work as finishing is in progress.

Still another object of the invention is the provision of a device using opposed abrasive elements to correct out of round surfaces which cannot be done with a single abrasive element.

An addition object of the invention is the provision of a device capable of correcting tapered work by applying more pressure where needed.

The above and other objects will appear more clearly from the following detailed description which when taken in connection with the accompanying drawings, will illustrate a preferred embodiment of the inventive idea.

Referring to the drawings:

Figure 1 is a front view of a device for external work only;

Figure 2 is a transverse, vertical section on line 2—2 of Figure 1;

Figure 3 is a section similar to Figure 2 of a device for internal work only.

In the drawings in which like characters of reference designate like or similar parts, Figures 1 and 2 illustrate a device embodying my invention and fitted for external work only. Numeral 2 denotes a member by which the device is mounted to the quill of any general purpose finishing machine which has facilities for revolving the work piece, oscillating and traversing an abrasive agent as a method of finishing and sizing.

The base member 2 is provided in each front corner with an opening in which a sleeve 4 is held by a set screw 6 threaded into the front face of the base and extending through sleeve 4 and adapted to bear with its inner end against

2

a stem 8. In each sleeve is slidably disposed a stem 8 which terminates at its lower end in a head 9. A bridge member 10 has an aperture at either end for one of the stems to which it is fixed, and rests upon the heads. An abrasive holder 12 is attached by fasteners 13 to the intermediate portion of the upper surface of the bridge member and holds an abrasive agent or stone 14 which has at its upper end a concave operative surface.

The upper ends of the sleeves project above the top surface of the base and are each surrounded by the lower turns of a coil spring 16. Each spring also encircles the upper end portion of the stem slidably disposed in the sleeve and bears with its upper end against the underside of an upper bridge member 17. The same has vertical openings in either end each for the upper end portion of a plunger 8 which is adjustably secured to the upper bridge member by a lock screw 18.

The intermediate portion 20 of the upper bridge member is thickened on either vertical side and has an upwardly extending threaded stem 21 upon which a nut 22 is threaded. The nut is held in adjusted position by the vertical leaf spring 23 which is attached by its horizontal part and a fastener 24 to the top surface of the upper bridge member.

The enlarged portion of the upper bridge member is provided with a vertical opening for a rod 26 of circular cross section which extends into spring sleeve 28 and supports with its upper end a compressive coil spring 30 housed in the sleeve. This spring bears with its upper end against a collar 31 affixed to the lower reduced end of a screw 32 which may be displaced in a nut 34. The nut is fixed by a pin 35 in the upper end of the sleeve and also engaged by a lock nut 36.

The rod 26 is diametrically apertured near its upper end for the insertion of a pin 38 which extends considerably beyond either side of the rod, and is secured in the lower ends of a pair of links 40. The upper end of either link is pivoted to the free end of a leg 41 of a U-shaped lever 42. The legs of the lever are each fulcrumed at an intermediate point upon a pin 43. These pins extend from opposite sides of a clamp 44 which is clamped by screw 45 upon the spring sleeve.

The lower portion of the sleeve is provided with a pair of registering slots 46 in which the end portions of pin 38 projecting beyond the rod are slidably disposed. The spring sleeve extends into

an annular space formed in the enlarged intermediate part of the upper bridge member and surrounding the rod. The rod 26 passes through a central vertical aperture in the intermediate part of the upper bridge member. The rod has below and coplanar with the opening for the pin 38 described another opening for a pin 47 the end portions of which extend outwardly on either side of the rod and may be engaged on their lower sides by the upper end of the nut 22 described.

The rod extends below the intermediate and enlarged portion of the upper bridge member and has a reduced lower end 48 extending into a central socket formed in the intermediate portion of the upper end of a support 49 which is slidably disposed in an aperture in the base and may be secured therein by a screw 50. A pin 51 connects the lower end of the rod to the support. To the lower end of the support is attached by fasteners 13 a holder 52 which extends laterally beyond the front and rear sides of the support and holds on its lower side an abrasive agent or stone 54.

To the upper bridge member is attached by screw 57 an adjustable actuating plunger 58 to be attached to any standard electronic measuring instrument.

The device can be used with or without the electronic measuring device which saves the time otherwise spent in removing the work piece from the machine for repeated checking.

The compression springs 16 between the upper bridge member and the base support the upper bridge 17 and the parts carried thereby resiliently so that their weight is not added to the pressure applied to the upper stone. These springs also carry the same weight when the stone is retracted from the work piece. Both abrasive agents may be positioned at a predetermined distance from the work piece by the setting of the screws 18.

Assuming that the set screws 18 are advanced for clamping the stems 8 to the upper bridge 17, that the set screws 6 are retracted so that the stems 8 can slide relatively to the sleeves 4 and to the base 2, and also that the set screw 50 is retracted, as seen in Figure 2, so that the support 49 can slide through the base 2, to operate the device as illustrated in Figures 1 and 2, the adjusting nut 22 is rotated in a direction for causing it to move downwardly on the threaded portion 21 and out of engagement with the stop pin 47. The lever 42 is then swung in a counter-clockwise direction as seen in Figure 1 so that the pivot of the lever 42 to the links 49 will cross the dead center of the pivots 38 and 43 to thereby release the parts so that the expansion spring 30 can expand. One end of the spring 30 seats against the collar 31 which is fixedly disposed relatively to the sleeve 28 by the parts 32, 34 and 35 whereas the opposite end of the spring seats against the upper end of the shank 26 for thereby urging the sleeve 28 and said shank 26 away from one another or upwardly and downwardly, respectively. This will cause the abrasive element 54, connected to the shank 26 by the support 49 to move downwardly and into engagement with the revolving work piece W, since the support 49 is slidable through the base 2 and the shank 26 is slidable in the sleeve 28 and the upper bridge 17. The upward movement of the sleeve 28 in response to the urgency of the spring 30 will at the same time carry the upper bridge 17 upwardly with said sleeve 28, due to the fact that the lower end thereof is secured in the stem 21 of the bridge 17. The bridge 17 in moving upwardly

will draw the stems 8 upwardly through the sleeves 4 and base 2 for moving the lower bridge 10 and lower abrasive element 14 upwardly with respect to the fixed support 2 so as to move said abrasive element 14 also into engagement with the rotating work piece W, so that both of said abrasive elements 14 and 54 will yieldably engage the work piece in opposed relationship to one another. This movement of the parts, as previously described, will cause the stop pin 47 and the nut 22 to approach one another and the spacing left therebetween after the abrasive elements are in engagement with the work piece will regulate the extent of the abrading operation on the work piece, since when the stop pin 47 engages the nut 22 the abrading elements will thereafter be prevented from moving further toward one another. The springs 16 function merely to support the upper bridge 17 and the parts carried thereby so that the operating spring 30 may act uniformly on the abrasive elements 14 and 54, as previously described, for yieldably holding each with the same amount of tension in engagement with the work piece.

The set screws 6 and 50 are utilized for locking the stems 8 and the support 49, respectively, when the lever 42 is in its position of Figure 1 for retaining the abrasive elements 14 and 54 in their retracted positions of Figures 1 and 2 and out of engagement with the work piece so that the abrasive elements may be brought into contact with a diamond truing bar, not shown, when diamond truing of the abrasive agents is required.

Figure 3 illustrates a slightly modified embodiment of the device intended for use for internal abrading and which is so analogous in construction to the embodiment, previously described and illustrated in Figures 1 and 2, that the modification has been illustrated only by a vertical sectional view, similar to Figure 2, and the parts of the device of Figure 3 which correspond or substantially correspond to the preferred embodiment of Figures 1 and 2 have been designated with a corresponding reference character except that the reference characters of the modification are primed. Accordingly, the fixed support is shown at 2' and one of the stems 8' is shown supporting the lower bridge 10' which rests upon the head 9' of said stem. An abrasive holder 12' is supported by the bridge 10' for mounting an abrasive element 14' on the underside thereof and in laterally offset relationship to the bridge 10'. The upper bridge 17' is yieldably supported above the supporting base 2' by springs 16', one of which is shown in Figure 3 and said bridge is provided with a laterally thickened central portion having an upstanding externally threaded extension 21'. A rod or shank 26' extends reciprocally through a bore of said thickened portion 20' and through its extension 21' and loosely through a nut 22' which adjustably and threadedly engages the extension 21'. The lower end of the sleeve 28' is anchored in a recess of the extension 21' to slidably receive the upper end of the rod 26' and said sleeve is provided with longitudinal slots 46' to slidably receive a stop pin 47' which extends diametrically through the rod 26' and outwardly through said slots 46'. A bolt or pin 38' extends through the rod 26' and has its ends projecting outwardly through the slots 46' and each of said ends pivotally engage an end of one of a pair of links 40' the opposite ends of which are pivotally connected to the free ends of the legs 41' of a U-shaped lever 42'. The legs 41' adjacent said free ends, are pivotally

connected to an adjustable clamp 44' by its pivot pins 43'.

An adjusting screw 32' is adjustably disposed in the upper end of the sleeve 28' by engagement with the threaded bore of a nut 34' which is secured in the upper end of said sleeve by a retaining pin 35', said adjusting screw being equipped with a lock nut 36', adapted to bear against the outer end of the nut 34'. The spring 30', contained in the sleeve 28' constitutes a contractile coil spring in counter distinction to the expansion coil spring 30 of the embodiment of Figures 1 and 2, and the upper end of said spring is suitably secured to the lower end of the screw 32', whereas the opposite end of the spring 30' is fastened to the upper end of the rod 26' by a headed screw 64.

A support or shank 49' is reciprocally disposed in the base 2' and may be secured relatively thereto by a set screw 50' which is normally retracted when the device is in use. The rod 26' has a restricted lower end 48' which extends into a socket in the upper end of the support 49' and which is connected thereto by a pin 51'. An abrasive support 52' corresponding to the support 12' is secured to the lower end of the support 49' and mounts an abrasive element 54' on the upper side thereof and in substantially the same vertical plane as the abrasive element 14'.

The nut 22' is provided with diametrically opposed openings 60' through which the pin 47' may be applied to or removed from the rod 26' and said pin is of a length to move longitudinally within the recess of the nut 22' between the extension 21' and an annular restriction 62 of the nut 22'.

The abrasive elements 14' and 54' are adapted to be positioned in the cylindrical bore of a work piece W' and, assuming the set screw 50' to be backed off and the stem 8' to be reciprocally disposed relatively to the base 2' and secured to the upper bridge 17', by swinging the lever 42' in a direction away from the operator, as seen in Figure 3, said lever will be rocked on its pivot 43' for causing the pivotal connection of the links 40' and legs 41' to cross the dead center of the pivots 38' and 43' to release the spring 30' so that it can urge the rod 26' upwardly and the sleeve 28' downwardly thereby to move the support 49' and support 52' upwardly toward the fixed base 2' for moving the abrasive element 54' into engagement with the bore of the work piece W' and at the same time the sleeve 28' in being drawn downwardly will force the bridge 17' downwardly toward the base 2' to cause the stems 8' to slide downwardly therethrough carrying the lower bridge 10' and support 12' for moving the abrasive element 14' likewise into engagement with the bore of the work piece. This will cause the pin 47' to move toward the stop flange 62 and when said parts engage further movement of the abrasive elements 14' and 54' away from one another under the biasing action of the spring 30' will be prevented. Thus, the pins 47' and the flange 62 of the nut 22' afford the positive stop for the embodiment of Figure 3 to limit the extent of the abrasive operation on the bore of the work piece. As in the previous embodiment, the springs 16' merely counterbalance the weight of the upper bridge 17' and the parts supported thereby so that both abrasive elements will engage the work with the same amount of pressure.

Various modifications and changes are contemplated and may obviously be resorted to, without departing from the spirit or scope of the in-

vention as hereinafter defined by the appended claims.

What I claim and desire to protect by Letters Patent is:

5. An abrasive device comprising a fixed support; an elongated frame, means connecting the frame to the support for reciprocating movement of the frame in the support in directions longitudinally of the frame, a first abrasive element connected to and supported by the frame and disposed transversely thereof, an abrasive support extending reciprocally through said fixed support and through a part of the frame and disposed for reciprocating movement relatively to the fixed support and frame in directions longitudinally of the frame, a second abrasive element secured to one end of the abrasive support disposed within the frame in opposed relationship to the first abrasive element for cooperation therewith, said abrasive elements being adapted to receive a workpiece therebetween which extends into the frame at a right angle to its longitudinal axis, a sleeve forming an extension of one end of the frame in which the other end of the abrasive support is reciprocally disposed and guided, an expansion spring disposed in said sleeve having one end abutting against said last mentioned end of the abrasive support, and said sleeve having a stop adjustably connected thereto against which the opposite end of said expansion spring abuts for yieldably urging the abrasive elements in opposite directions and toward one another.
10. A device as in claim 1, a link pivotally connected to the abrasive support, and a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position.
15. A device as in claim 1, a stop pin extending transversely through a part of the abrasive support, said frame having a transverse portion through which the abrasive support slidably extends, and a threaded collar connected to said transverse portion and adjustable thereon longitudinally of the abrasive support and disposed in the path of movement of the stop pin when the abrasive support is displaced toward said first abrasive element for limiting the extent of movement of the abrasive support and second abrasive element toward said first abrasive element.
20. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
25. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
30. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
35. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
40. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
45. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
50. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
55. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
60. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
65. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
70. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said
75. A device as in claim 1, a link pivotally connected to the abrasive support, a lever pivotally connected to said sleeve and having one end pivotally connected to the link in spaced relationship to its first mentioned pivot and forming a mechanical connection between the frame and abrasive support, said lever being swingable in one direction to exert a pull on the link to move the abrasive support in a direction for retracting the second abrasive element away from the first abrasive element and for moving the link across the pivot point of the lever for latching the abrasive support in a retracted position, a stop pin extending transversely through a part of the abrasive support, said frame having a transverse portion through which the abrasive support slidably extends, and a threaded collar connected to said

transverse portion and adjustable thereon longitudinally of the abrasive support and disposed in the path of movement of the stop pin when the abrasive support is displaced toward said first abrasive element for limiting the extent of movement of the abrasive support and second abrasive element toward said first abrasive element.

5. A device as in claim 1, said frame being disposed with its longitudinal axis in a vertical plane and with said abrasive elements in vertically spaced relationship, and spring means engaging on the fixed support and bearing against a part of the frame disposed thereabove and yieldably supporting the frame relatively to the fixed support to counterbalance the weight of the frame and parts supported thereby.
